United States Patent Office

Des. 212,924
Patented Dec. 10, 1968

212,924

BED SHEET OR SIMILAR ARTICLE OF BED LINEN

Connie C. Willoughby, New York, N.Y., assignor to Cannon Mills Company, Kannapolis, N.C., a corporation of North Carolina

Filed July 17, 1967, Ser. No. 7,823

Term of patent 14 years

(Cl. D92—26)

The reverse side of the bed sheet is substantially plain and unornamented.

I claim:

The ornamental design for a bed sheet or similar article of bed linen, substantially as shown and described.
